(57) **CLAIM**

The ornamental design for display screen with animated graphical user interface, as shown and described.

DESCRIPTION

The patent or application file contains at least one drawing executed in color. Copies of this patent or patent application publication with color drawing(s) will be provided by the Office upon request and payment of the necessary fee.

1. Display screen with animated graphical user interface

1.1 : Front

1.2 : Front view in changed state

1.3 : Enlarged

The appearance of the transitional image sequentially transitions between the images shown in reproductions 1.1-1.2. The process or period in which one image transitions to another image forms no part of the claimed design.

The broken lines immediately adjacent the shaded areas showing a display screen represent the bounds of the claimed design and form no part thereof while all other broken lines show an electronic device forming no part of the claimed design.
